UNITED STATES PATENT OFFICE.

HERMAN A. POPPENHUSEN, OF HAMMOND, INDIANA.

METHOD AND APPARATUS FOR COMBINING MOLTEN METAL WITH A GAS.

Application filed March 26, 1924. Serial No. 701,901.

This invention relates to a method of and apparatus for chemically combining a molten metal with a gas, as for instance molten lead with air to make lead oxid, or with a 5 carbonic gas to make lead carbonate.

The main object of my invention is to direct a blast of the gas across and in contact with an exposed surface of the molten metal to continuously clear the surface of the resultant compound formed by the chemical combination of the molten metal and the gas so as to present fresh surfaces of molten metal to the action of the gas.

A further object of my invention is to 15 utilize the lifting effect of the blast on the exposed surface of the molten metal to determine or control the rate of metal feed thereto, thus affording no opportunity for the blast to blow off more molten metal than 20 can be chemically combined with the blast.

Other and further objects of my invention will appear from the following specification, taken in connection with the accompanying drawings, in which—

25 Fig. 1 is a longitudinal vertical sectional view taken through an apparatus for practicing my invention;

Fig. 2 is a horizontal sectional view taken on line 2—2 of Fig. 1;

30 Fig. 3 is an enlarged vertical sectional view through one of the atomizers of the apparatus; and

Fig. 4 illustrates a valve structure to be hereinafter described.

35 The apparatus of my invention comprises a pot or kettle 1 beneath which is a burner 2 or other source of heat for keeping molten the metal in said pot. The latter is constantly supplied with molten metal from a 40 second pot or kettle 3 through a connecting conduit or pipe connection 4, as shown in Fig. 1. Beneath the pot 3 is a burner 5 for keeping molten the metal therein. The pots or kettles 1 and 3 are arranged side by side 45 and are supported in place by upright walls 6, 6 of a suitable surrounding furnace setting, as shown in Fig. 1.

Over the pot 1 is a conical cover 7 opening upward into an outlet conduit 8 leading to 50 a collecting hopper 9 having a screened gas outlet 10 at its upper end and a gate controlled discharge spout 11 at its lower end. The normal level of the molten metal in the pot 1 is indicated by α , and arranged 55 above that level is a shield 12 to exclude air from the molten metal below the same.

Said shield 12 is made of metal and is supported in place in any suitable manner as by inwardly projecting lugs 13, 13 on the side walls of the pot 1 above the molten 60 metal therein.

Carried by the shield 12 are a plurality of vertical or upright pipes or tubes 14, 14 extending down and opening into the molten metal in the pot 1. The tubes 14 extend 65 above the shield 12 and have their upper ends opening into the space or chamber between the cover 7 and shield 12. As indicated in Fig. 2, the tubes 14 are arranged in a circle around the shield and are spaced 70 apart circumferentially.

Associated with the tubes 14 are blast conduits or pipes 15, 15, one for each tube 14 and extending through the shield 12. Said conduits 15 are arranged outside of 75 the tubes 14 and each has its upper end bent to provide a nozzle 16 extending toward its associate tube 14. The nozzles 16 are at angles to the tubes 14 and are arranged to direct streams of gas across the 80 open upper ends thereof.

The conduits 15 extend downward into the molten metal in the pot 1, and each conduit has a coiled section 17 submerged in the molten metal in said pot 1 to heat the 85 gas passing therethrough to approximately the same temperature as the molten metal in said pot. Each coil 17 is connected by a pipe 18 with a blast ring 19 outside of and above the cover 7. The ring 19 has a supply 90 pipe 20 leading to a blower or other source of air or gas supply (not shown). In reaching the coils 17, the pipes 18 extend down into the molten metal, as shown, and constitute portions of the gas blowing conduits. 95

When using the apparatus shown and described to make lead oxid, air under pressure is supplied to the ring 19, and from thence is blown from the nozzles 16 across the open 100 upper ends of the tubes 14. In operation, the atomizing action of the air blasts on the tubes 14 creates partial vacuums in the tubes 14 to lift a column of molten metal from the pot 1 in each tube 14 to the upper end thereof. The air blowing across the surfaces of molten metal maintained at the open upper ends of the tubes 14 by chemical 105 action converts the molten metal acted on into lead oxid and, in blowing off portions 110 of molten metal as sprays, completely converts all of the molten lead acted on into

lead oxid. All the nozzles 16 discharge toward the center of the shield 12, where the free air meets and by its resultant action creates an upward flow into the conduit 8. 5 This flow carries the lead oxid through said conduit 8 into the hopper 9, where it is deposited, the excess air escaping to the atmosphere through the screen 10. To facilitate this upward flow, the nozzles 16 are inclined 10 upward, and the upper ends of the tubes 14 are formed to extend into the air blasts, as shown in Fig. 3.

For making lead carbonate, that is, white lead, a carbonic gas is passed through the 15 nozzles 16, a certain proportion of the carbonic acid uniting with the exposed molten lead to make lead carbonate, which is collected in the hopper 9.

For chemically combining any other metal 20 with any other gas, the desired metal is melted in the pot or kettle 1 and the required gas is blown through the nozzles 16 over the tubes 14.

In combining molten metal with a gas by 25 the method and apparatus of my invention, the atomizing or lifting action of the gas blasts on the upper ends of the tubes 14 continuously presents fresh surfaces of molten metal to the blasts as the resultant 30 compound formed by the chemical combination of the molten metal and gas is blown off the same. This is an important factor of my invention because the feed of molten metal to the blasts is automatically controlled 35 thereby and proportionate to the amounts of compound produced. Manifestly, complete conversion of the molten metal takes place because no opportunity is afforded for feeding any more metal into the blasts than can 40 be chemically combined therewith and under conditions of an excess of gas always about and available for complete oxidation of the finely divided particles of sprayed metal, thus making both practical and efficient the 45 method and apparatus of my invention.

The pot or kettle 3 may have a cover 21. The cover 7 may have a layer of suitable heat insulating material 22 on its outside to retain heat therein. In Fig. 4 is shown 50 a valve arrangement for mechanically controlling the metal feed to the gas blasts independent of the lifting effect of the latter on the molten metal in the tubes 14. As illustrated, a conical valve member 23 is provided at the lower end of the tube 14 and moved into and out of the open end thereof by a rod 24 carrying said valve. Said rod is outside the tube and is slidably mounted in brackets 25, 26 on the tube, one 55 below the shield 12 and the other above the same. Between the shield and upper bracket 60 is a nut 27 on a threaded portion of the rod for moving the same endwise in adjusting the valve 23. To hold the rod against 65 turning with the nut, the upper end of the

rod is square and in a like shaped opening in a bracket 28 on the shield 12. This valve mechanism could be applied to each of the tubes 14, and operated separately for each tube or connected in a manner suitable for 70 simultaneous operation.

The apparatus shown and described may be variously changed and modified without departing from the spirit and scope of my 75 invention.

I claim as my invention:

1. The method for combining a molten metal with a gas, consisting in directing a blast of gas across the open end of a tube 80 communicating with a supply of molten metal for inducing a flow of molten metal to the open end of said tube for contact with the gas.

2. The method for combining a molten metal with a gas, consisting in directing a 85 blast of gas across the open end of a tube communicating with a supply of molten metal for inducing a flow of molten metal to the open end of said tube for contact with the gas and controlling the supply of molten 90 metal coming in contact with the blast.

3. The method of chemically combining a molten metal and a gas, consisting in directing a continuous blast of the gas across and 95 in contact with an exposed surface of a supply of the molten metal to continuously clear the surface of the resultant compound formed by the chemical combination of the metal and gas so as to present fresh surfaces 100 of molten metal to the action of the gas, the lifting effect of the blast on the exposed surface determining the rate of metal feed thereto.

4. The method of chemically combining a molten metal and a gas, consisting in directing a continuous blast of the gas across the upper end of a tube rising from a supply 105 of the molten metal to continuously feed molten metal into contact with the gas at the upper end of the tube as the resultant compound formed by the chemical combination of the molten metal and gas is blown from the metal surface at said tube end.

5. The method of chemically combining a molten metal and a gas, consisting in directing a continuous blast of the gas across the upper end of a tube rising from a supply of 115 the molten metal to continuously feed molten metal into contact with the gas at the upper end of the tube as the resultant compound formed by the chemical combination of the molten metal and gas is blown from the metal surface at said tube end, and heating the gas to approximately the same temperature as the molten metal before being 120 blown into contact therewith.

6. The method of chemically combining a molten metal and a gas, consisting in directing a continuous blast of the gas across the upper end of a tube rising from a supply of 130

the molten metal to continuously feed molten metal into contact with the gas at the upper end of the tube as the resultant compound formed by the chemical combination of the molten metal and gas is blown from the metal surface at said tube end, and heating the gas to approximately the same temperature as the molten metal before being blown into contact therewith by passing the 10 gas through a conduit, a portion of which is submerged in the molten metal.

7. The method of making lead oxid, consisting in directing a continuous blast of heated air across the upper end of a tube 15 rising from a supply of molten lead to continuously feed molten lead into contact with said heated air at the upper end of said tube as the oxid is blown from the metal surface at said tube end.

20 8. In an apparatus of the character described, the combination of a supply kettle containing molten metal, a tube rising out of the molten metal, and means for directing a blast of gas across the upper end of said tube to bring molten metal through the tube into contact with the gas at the upper end thereof.

9. In an apparatus of the character described, the combination of a supply kettle 30 containing molten metal, a tube rising out of the molten metal, and a conduit for directing a blast of gas across the upper end of said tube to feed molten metal into contact with said gas at the upper end of said tube, said conduit having a coiled portion submerged in the molten metal to heat the gas before being discharged across said tube.

10. In an apparatus of the character described, the combination of a supply kettle 40 containing molten metal, a cover over said kettle, a shield over the molten metal below said cover to exclude air from the molten metal, a tube carried by and extending through said shield into the molten metal, and means in the space between the shield and cover for directing a blast of gas across the upper end of said tube to feed molten metal through the tube into contact with the gas, said cover having an outlet opening for

the removal of the resultant compound 50 formed by the chemical combination of the molten metal and gas.

11. In an apparatus of the character described, the combination of a supply kettle containing molten metal, a cover over said kettle, a shield over the molten metal below said cover to exclude air from the molten metal, and means, including gas blasts, for lifting molten metal into the space between the shield and cover at a plurality of points 55 about the same for chemically combining the molten metal and gas by blowing the latter into contact with the former, said means causing the blasts of gas to be discharged toward a common meeting point 60 65 so that the resultant stream created thereby will flow through the outlet in the cover.

12. In an apparatus of the character described, the combination of a kettle containing molten metal, a cover over said kettle 70 and having an outlet conduit, a shield between the molten metal and cover, a plurality of tubes carried by and extending through the shield into the molten metal, and gas conveying conduits having nozzle 75 ends above said shield and arranged to discharge blasts of gas across the open upper ends of said tubes to feed molten metal into contact with said blasts, said nozzles and tubes being arranged that the discharge is 80 toward a common meeting point above said shield so that the resultant stream created thereby will flow out of said outlet conduit.

13. In an apparatus of the character described, the combination of a kettle containing molten metal, a tube rising out of said molten metal, means for directing a blast of gas across the upper end of said tube to bring molten metal through the tube into contact with the gas at the upper end thereof, and valve means associated with said tube for mechanically controlling the supply of metal thereto.

In testimony that I claim the foregoing as my invention, I affix my signature this 95 24th day of March, 1924.

HERMAN A. POPPENHUSEN.
